8-BROMOTHEOPHYLLINE SALT OF 2-AMINO-2-METHYL-1-PROPANOL

James M. Holbert, Lookout Mountain, and Irvine W. Grote, Chattanooga, Tenn., assignors to The Chattanooga Medicine Company, Chattanooga, Tenn., a corporation of Tennessee

No Drawing. Application November 19, 1952,
Serial No. 321,498

1 Claim. (Cl. 260—253)

The present invention relates to a pharmaceutical compound having enhanced diuretic activity, and more particularly, to the compound: 8-bromotheophylline-2-amino-2-methyl-1-propanol, which is a bromotheophylline salt of 2-amino-2-methyl-1-propanol. These compounds have the following structural formulas:

The salt of these two compounds may be called 2-amino-2-methyl-1-propanol 8-bromotheophyllinate or 8-bromotheophylline-2-amino-2-methyl-1-propanol.

We are aware that theophylline itself has previously been combined with various amines for the purpose of solubilizing the theophylline in diuretic compositions. Probably the most common derivative of this type is theophylline-ethylene diamine, known under the commercial name "Aminophylline."

We are also aware that U. S. Patent No. 2,404,319, issued July 16, 1946, to Robert S. Shelton, discloses and claims the theophylline salt of 2-methyl-2-amino-1-propanol, alleging that this compound is superior to "Aminophylline" as a therapeutic agent.

We have now found that, if the theophylline of this type of composition is replaced by a halotheophylline, particularly 8-bromotheophylline, not only is the solubility of the resulting composition increased to a greater degree than occurs from the reaction between theophylline and the same amine compound, particularly 2-methyl-2-amino-1-propanol, but the resulting salt is far superior as a diuretic compound to the previously known diuretic compounds containing theophylline.

The remarkably increased diuretic properties of the halotheophylline-amine salt of the present invention makes it a valuable therapeutic agent in the relief of premenstrual tension, a condition upon which previously known derivatives of theophylline had little or no effect.

A large percentage of women, estimated at 30 to 60% suffer from premenstrual tension in varying degrees during the menstrual age. These women accumulate water in the body tissues during the week preceding the menses in varying amounts, the amount usually varying from 1 to 5 pounds. The symptoms of such water accumulation are headache, breast fullness and soreness, abdominal distension, low back pain, extreme nervousness, swelling of the ankles, increased appetite, irritability, pelvic pain, and a feeling of tension. The severity of the discomfort is directly commensurate with the amount of fluid accumulated or pounds of weight gained. Women who gain from 3½ to 4 pounds during the week preceding the menses are almost incapacitated due to the severity of the symptoms from water toxemia.

The compound of the present invention is singularly efficient in the relief of the symptoms associated with premenstrual tension. Patients to whom the com-

2

ound of the present invention is administered approximately one week before the onset of menses rarely gain more than one and one-half pounds, and in many cases no weight gain whatsoever is observed. Furthermore, patients who are placed under treatment with the product of the present invention, even after they have gained weight, have a diuresis within a few hours after beginning treatment, resulting in the prompt relief of the symptoms.

One outstanding characteristic of the therapeutic product of the present invention in the treatment of premenstrual tension is that in most patients it prevents water accumulation without diuresis if the treatment is started early enough so that the patients have no symptoms of water toxemia throughout their premenstrual period.

An object of the present invention is to provide a therapeutic product comprising a halotheophylline salt of an organic amine, namely, the 8-bromotheophylline salt of 2-amino-2-methyl-1-propanol, for use in the relief of premenstrual tension without the presence of side reactions usually associated with the administration of theophylline.

Another object of the present invention is to provide a compound capable of effecting unlocking pitressin-induced edema in human females.

Another object of the present invention is to provide a "theophylline type" derivative having a high water solubility and a high degree of diuretic activity.

Still another object of the present invention is to provide a diuretic composition of enhanced activity which is capable not only of releasing added water but previously retained water from human body tissues.

The compound of this invention is prepared by reacting 8-bromotheophylline with 2-methyl-2-amino-1-propanol, for example, as follows:

Two hundred and fifty-nine grams (equal to 1 mole) of 8-bromotheophylline are suspended in one liter of water. To this suspension are added eighty-nine grams (1 mole) of 2-amino-2-methyl-1-propanol. The mixture is well stirred and if necessary complete solution is effected with gentle heat. The solution is filtered to remove any suspended matter and taken to dryness at reduced temperature and pressure. The resulting solid is dried to a constant weight in a drying oven and ground to a fine powder.

This material is assayed for its bromotheophylline content by the procedure given for chlorotheophylline in N. N. R. (1951) p. 537. Analysis of the material showed a bromotheophylline content of 74.07%. This is compared to a theoretical bromotheophylline content of 74.40% if the reactant is combined in a molar ratio of 1 to 1. Therefore it is concluded that a true molecular compound has been formed consisting of one mole of bromotheophylline combined with one mole of 2-amino-2-methyl-1-propanol according to the following formula:

The compound decomposes rather sharply at 300° C. The solubility in water at room temperature exceeds 30 g./100 cc. to give a solution having a pH of around 8 to 8.5.

In testing the compound of the present invention for its diuretic action, the following procedure was used:

When rats are given tap water perorally on the basis of 5 cc. of water per 100 g. of body weight of each rat, on the average of 100% of the water so given will be excreted as urine over a four-hour period. If, in addition to the water, the rats are each given sub-

cutaneously $\frac{1}{2}$ unit of pitressin, an anti-diuretic drug, only 42% of the water, on the average, will be excreted. In conducting this test, the drug to be tested is given in a dosage on the basis of 0.1 g. of the product per kilogram body weight of the rat and the product is added in this proportion to the water and pitressin. In this way, the anti-pitressin action of each of the various compounds is tested in terms of the per cent of water recovery from the rats.

It was found that the diuretic activity of 8-bromotheophylline-2-amino-2-methyl-1-propanol was 116; whereas the diuretic activity of the corresponding theophylline salt: theophylline-2-amino-2-methyl-1-propanol was only 66, under the same test conditions. These results are even more startling when the molar proportions of theophylline per se are considered since one gram of bromotheophylline is equivalent on this basis to only about $\frac{3}{4}$ gram of theophylline U. S. P.

A more elaborate series of tests were run substantially as the test hereinbefore described was run; and the results obtained are shown on the table (below), wherein column (1) shows the dosage of the theophylline or bromotheophylline used in each test, and column (2) shows the percentage water recovery calculated by dividing the total volume of water given to a cage (of 4 rats each, which is the number of rats employed to obtain each test figure on the table) into the volume of urine collected in the following 4 hours. Columns (3), (4), (5) and (6) show, respectively, the total sodium (Na), potassium (K), chloride (Cl), and sodium plus potassium, in milli-equivalent weights, per cage of four rats that was found in the urine recovered during the 4-hour period. Section A shows the results using plain tap water; Section B shows the results using plain tap water plus the subcutaneous pitressin injection hereinbefore described; Section C shows the results using plain water plus pitressin as in Section B and also using the amounts of the theophylline salt specified; and Section D compares with Section C, using in this instance the bromotheophylline salt of the invention instead of the theophylline salt.

Table

SECTION A—WATER

It will be seen from the table above that in each instance, the percent water recovery as well as the salt diuresis is distinctly greater for the bromotheophylline drug. An additional important point is that dosages of the theophylline drug in excess of the 3 mg. level could not be administered to the rats without introducing considerable toxic symptoms in the test animals. It is thus clear that the bromotheophylline drug gives superior as well as different results, in that it can be given in large dosages.

It has also been found that the instant bromotheophylline salt gives a unique physiological action that is different from the general action characteristic of theophylline drugs. It has been established that the major effect of xanthine drugs, including theophylline, is on the circulation, which, in turn, causes increased transport conditions connected with the waste materials including water and salt. Under appropriate conditions the renal circulation becomes affected, and a diuretic effect may be obtained; but such action, whether or not directly on the renal cells, is clearly not the major action of these drugs.

In view of the fact that the increased renal function results, if at all in the case of these drugs, from changes in the generalized transport situation, it follows that the renal action induced is variable, depending upon many other factors affecting the transport situation which may divert major transport effects to other areas of the body, such as the skin.

Tests have revealed that both the theophylline and the bromotheophylline drugs show an increase in total weight loss in a test animal, but that with the theophylline drug the loss may be extra-renal as well as renal, whereas in the case of the instant bromotheophylline drug the losses are almost exclusively renal. Extra-renal weight loss, known to be due largely to transpiration through the skin, is markedly increased under theophylline action in hot weather to such an extent that the renal action may be decreased, or even markedly inhibited, as compared to normal controls. Using the bromotheophylline drug, however, this action does not take place, thereby showing that this drug possesses a unique focussing or localizing effect upon kidney function. This function is valuable because it provides a new standardizing agent for comparative studies on kidney function. Also, tests show that in hot weather the salt diuresis effected by the bromotheophylline drug is consistently high (compared to the

theophylline drug), and that the pH of the urine consistently indicates that the kidneys have been caused to do work in the case of the instant drug whereas this is not so in the case of the corresponding theophylline drug.

The diuretic activity of a compound, as measured by the above test, is a good indication of its effectiveness in the relief of premenstrual tension among human females. The relief of premenstrual tension by the diuretic compound of the present invention may be explained when it is appreciated that premenstrual tension is a symptom-complex related to abnormal water storage during the premenstrual period and is essentially a water toxemia. The intensity of these symptoms varies directly as the amount of water retained, and relief of the symptoms accompanies the diuresis.

It will be understood that modifications and variations may be effected without departing from the scope of the novel concepts of the present invention.

We claim as our invention:

The 8-bromotheophylline salt of 2-amino-2-methyl-1-propanol.
